UNITED STATES PATENT OFFICE.

CHARLES W. HARMAN AND EDWIN T. HARMAN, OF NEW ROCHELLE, NEW YORK,
ASSIGNORS TO JOSEPH FAHYS & COMPANY, OF NEW YORK, N. Y., A CORPORATION OF NEW YORK.

WATCHCASE.

1,357,978.

Specification of Letters Patent.

Patented Nov. 9, 1920.

Application filed July 2, 1920. Serial No. 393,480.

To all whom it may concern:

Be it known that we, CHARLES W. HARMAN and EDWIN T. HARMAN, citizens of the United States, and residents of New 5 Rochelle, county of Westchester, State of New York, have invented certain new and useful Improvements in Watchcases, of which the following is a specification:

The present invention relates to improvements in watch cases—particularly for wrist watches—and to the means for supporting the case upon the wrist-band or ribbon whereby the appearance of the watch both as to its size and shape will be modified 15 with a view to improving the artistic effect.

A watch case normally comprises three parts, namely, the center, the back and the bezel. Wrist watch cases commonly have the loops for the attachment of the wrist-band or ribbon secured to the watch center so that when the watch is in place, the entire 20 face design of the watch is exposed. In the improved watch case of the present application, the securing loops for the wrist band 25 or ribbon are mounted upon the watch bezel and project over portions of the bezel face with the result that when the wrist-band or ribbon is attached, the loop-end portions thereof will extend over and conceal portions 30 of the bezel face and modify the appearance of the design of the watch both as to its size and shape.

In coöperation with the loop bars upon the bezel, we sometimes provide additional 35 loop bars upon the watch center with a view to increasing the safety of the attachment of the wrist-band or ribbon to the watch and avoid the result of the accidental separation of the bezel from the case when 40 the watch is removed.

In order that the invention may be fully understood, we will first describe the same with reference to the accompanying drawing and afterward point out the novelty in 45 the annexed claims. In said drawing:—

Figure 1 is a face view of one form of the improved watch case for wrist watches.

Figs. 2 and 3 are different edge views of the same.

Fig. 4 is a face view of a modified form 50 of the improved watch case.

Figs. 5 and 6 are different edge views of the form shown in Fig. 4.

Referring first to the watch case illustrated in Figs. 1, 2 and 3 of the drawing, 1 is the 55 watch center, 2 the back and 3 the bezel of the watch case of general octagonal form. The bezel 3 may have a dial opening of any desired shape or design but in the present case, it has a generally oblong face opening 60 4 outlined by the raised frame or flat 5. The frame 5 supports the crystal or transparency in the usual way. Mounted upon the face of the bezel 3 and extending parallel with the long sides of the face frame 5 65 are the metal bars or loops 6 which are preferably formed flush with the frame or flat 5 and spaced slightly therefrom as indicated at 7. These loops 6 are designed to have threaded through them the ribbon, web, 70 strap or other form of attaching wrist-band indicated at 8 by which the watch case can be mounted upon the wrist of the wearer.

It will be observed, particularly with reference to Fig. 1 of the drawing, that when 75 the wrist-band or ribbon 8 is properly threaded through the loops 6, the side portions of the watch case and particularly the watch bezel are covered by the band or ribbon so that the shape and size of the watch 80 case are materially modified in appearance.

In Figs. 4, 5 and 6 of the drawing, we show a modified form of case embodying the present invention. This modification is illustrated as applied to a "cushion" design 85 of watch case, although it will be understood that the design is immaterial. In this modification, the case center 10 is provided with the usual loop bars 11 while the bezel 12 is provided with the loop bars 13 attached to the bezel and projecting across parts of the face thereof for the purpose of concealing the shape and size of the case beneath the ends of the wrist-band or ribbon as in the form shown in Figs. 1, 2 and 3. 90 In attaching the wrist-band 15 to this modified form of case, the same is threaded through both loops 11 and 13, as illustrated in Fig. 5. In this form of case, the ribbon or band 15 engaging the loops on both the 1 center and bezel, will prevent the accidental separation of the bezel from the case when the watch is removed from the wrist of the wearer.

The main purpose of the present invention is to provide a novel and artistic watch

case for wrist watches in which watch movements, as now constructed, can be readily mounted.

We claim:—

- 5 1. A three-piece wrist watch case having band attaching loops or bars projecting over parts of the bezel to disguise the shape and size of the watch.
- 10 2. A wrist watch case having loops or bars attached to a part of the case and projecting over portions of the bezel, and a web or band attached to said loops or bars and covering parts of the bezel to disguise the size and shape of the watch case.
- 15 3. A wrist watch case having a center, a back, and a bezel, loops or bars attached to

the bezel and projecting over parts of the face thereof, loop bars attached to the center in operative relation to said bezel loop bars, and a band passing through said loops and 20 extending over portions of the bezel face to disguise the shape and size of the watch.

4. A wrist watch having a center, a back, and a bezel, a loop bar attached to the bezel and projecting over a part of the face thereof, a loop bar attached to the center in operative relation to said bezel loop bar, and a band passing through said loops and 25 extending over a portion of the bezel face to disguise the shape and size of the watch.

CHARLES W. HARMAN.
EDWIN T. HARMAN.
